US00D603853S

(12) **United States Design Patent**
Lee

(10) **Patent No.:** US D603,853 S
(45) **Date of Patent:** ** Nov. 10, 2009

(54) **KEYPAD FOR A MOBILE PHONE**

(75) Inventor: **Sang-Yong Lee**, Seoul (KR)

(73) Assignee: **Samsung Electronics Co., Ltd.**,
Suwon-Si (KR)

(**) Term: **14 Years**

(21) Appl. No.: **29/328,787**

(22) Filed: **Dec. 2, 2008**

(30) **Foreign Application Priority Data**

Sep. 18, 2008 (KR) 30-2008-0040304

(51) **LOC (9) Cl.** 14-03

(52) **U.S. Cl.** D14/247

(57) **CLAIM**

The ornamental design for a keypad for a mobile phone, as shown and described.

DESCRIPTION

FIG. 1 is a front perspective view of a keypad for a mobile phone;

FIG. 2 is a front view of the keypad for a mobile phone of FIG. 1;

FIG. 3 is a rear view of the keypad for a mobile phone of FIG. 1;

FIG. 4 is a left-side view of the keypad for a mobile phone of FIG. 1;

FIG. 5 is a right-side view of the keypad for a mobile phone of FIG. 1;

FIG. 6 is a top plan view of the keypad for a mobile phone of FIG. 1; and,

FIG. 7 is a bottom plan view of the keypad for a mobile phone of FIG. 1.

The keypad design consists of the outermost solid line boundary and everything within. The broken line showing of the remainder of the handset is directed to environment and is for illustrative purposes only; the broken lines form no part of the claimed design.
